US00D553002S

(12) **United States Design Patent** (10) **Patent No.:** **US D553,002 S**
(45) **Date of Patent:** **** Oct. 16, 2007**

(54) **CONTAINER WITH A CLIP FOR AEROSOL CANS**

(75) Inventor: **Josef Petek**, Flawil (CH)

(73) Assignee: **e+h Services AG**, Daeniken SO (CH)

(**) Term: **14 Years**

(21) Appl. No.: **29/221,746**

(22) Filed: **Jan. 18, 2005**

Related U.S. Application Data

(62) Division of application No. 29/188,012, filed on Aug. 11, 2003, now Pat. No. Des. 511,974.

(30) **Foreign Application Priority Data**

Feb. 11, 2003 (CH) 129358

(51) **LOC (8) Cl.** **09-01**

(52) **U.S. Cl.** **D9/682**

(58) **Field of Classification Search** D9/522, D9/538, 682, 686-691, 726; 222/260, 321.3, 222/321.7, 383.1, 556

(57) **CLAIM**

The ornamental designs for a container with a clip for aerosol cans, as shown and described.

DESCRIPTION

FIG. 1 is the left side view of a container with a clip for aerosol cans, showing my new design;

FIG. 2 is a front view thereof;

FIG. 3 is a bottom view thereof;

FIG. 4 is a top view thereof;

FIG. 5 is an elevated perspective view thereof;

FIG. 6 is an elevated rear perspective view thereof;

FIG. 7 is a right side view thereof;

FIG. 8 is a rear view thereof;

FIG. 9 is a left side view of a second embodiment of a container with a clip for aerosol cans;

FIG. 10 is a front view of FIG. 9;

FIG. 11 is a bottom view of FIG. 9;

FIG. 12 is a top view of FIG. 9;

FIG. 13 is an elevated perspective front view of FIG. 9;

FIG. 14 is an elevated rear perspective view of FIG. 9;

FIG. 15 is a right side view of FIG. 9; and,

FIG. 16 is a rear view of FIG. 9.
